PLAYGROUND CLIMBING APPARATUS

George H. Goundie and Howard C. Schroeder, Milwaukee, Wis., assignors to Creative Playstructures, Inc., Milwaukee, Wis., a corporation of Wisconsin

Application September 2, 1958, Serial No. 52,466

Term of patent 7 years

(Cl. D34—5)

Fig. 1 is a perspective view of a playground climbing apparatus, showing our new design;

Fig. 2 is a top plan view;

Fig. 3 is a transverse sectional view taken on the line 3—3 of Fig. 1;

Fig. 4 is a transverse sectional view taken on the line 4—4 of Fig. 1; and

Fig. 5 is a transverse sectional view taken on the line 5—5 of Fig. 1.

The broken line showing in Fig. 1 of the drawing represents normally concealed base parts of the apparatus, and is for illustrative purposes only.

The dominant features of the invention are those shown in full lines in the drawing.

We claim:

The ornamental design for a playground climbing apparatus, substantially as shown and described.
